(54) **HULLING RICE, POLISHING**

(76) Inventor: **William Scarbrough**

William Scarbrough Savannah, Ga.
Letters Patent

The Schedule referred to in these Letters Patent and making part of the same
containing a description to the word of the said William Scarbrough issuing
of his Improvement in the Cleaning and polishing or burnishing of Rice

To all whom these Presents shall come, Be it known that I William Scarbrough of the City of Savannah in Chatham County State of Georgia have invented a new and useful Improvement in the Cleaning and polishing or burnishing of Rice and that the following is a full and exact description thereof.

Various & infinite & ingenious as have been the contrivances which have hitherto been devised and applied to the cleaning of Rice from the pell-mell or skin render the one to bush and preparing the same for a foreign or domestic market no plan hitherto employed or tried has, in any degree of time effectively answered the desired purpose except that of pounding the rice in Mortars. This has formerly been done by hand in simple Mortars but of late years falling pestles raised by the arms of a Halloway in the Dutch clay Bed oil Cake stamping mill supplied by animal, water or steam power have been advantageously used and in some few instances pestles have been used on by cranks but in all and every case the rough rice had in the first instance to be cleaned of its outer coat or hull by passing it between revolving rollers of sand stone or other materials kept sufficient by apart from each other to prevent the breaking or splitting of the grain in the operation. The cause of the failure of success in all the other modes or plans hitherto employed has in the first instance originated in the insufficiency of the materials or substances applied for the purpose to successively sustain the principal friction of the chaff or outer coat of the grains of rice and, ~~nor~~ ^{nor} at all, its agency and assistance (even in the Mortar where it is employed) the cleaned rice can never be made sufficiently or satisfactorily bright or peart for advantageous market. The industry of grain or species

projections in the Convex O_{pposites} or the best temporal, still more similar to that used for Cotton or Wool Cards are either entirely worn away or smoothed & polished by the roughing of the Cloth so as to become imperceptible in a period of time, very little exceeding that in which the same effect would be produced on the same material by the operation of such suspended files; and when the smooth surface has once taken place the desired effect in the cleaning of the rice, may in - great measure be considered as at an end. Another but a subordinate cause of the insufficiency of the mode or place hitherto used, Mortar & Mortar, used to be the large proportion of the grains of the rice which escaped the operation of the first hulling, and might have been removed by this hulling, but which still retain their rarer & rarer, although they have lost their roughness, and have then become smoothed by the subsequent operation.

These grains it has been found next to impossible to separate from the cleaned rice, and by the process of hand picking the labour and expense of which would be entirely to great, but notwithstanding the presence of these uncleaned grains are intrinsically a quality of very trivial importance still they tend to depreciate the rice in the market.

Some preliminary remarks have, have been made in order to render more readily comprehensible the system of rice cleaning now proposed and to support for the benefit of others the result of some observations experience. The mode of operation for the cleaning and preparing of rice as now proposed is after the rough rice as it is here to be supplied as it is elsewhere called has been hulled in a manner as above stated and now in common use either to subject it to from 10 to 20 minutes boiling in the Mortar (but this is not deemed essential) and then or at once after the operation of the hulling to transfer it to another bed of rubber, one of which set at the least shall be of stone. Whether the upper or rubber, rubber be made to revolve, we are speaking of horizontal, rubber, if these rubber, shall be all the better for a low mass of stone or other material offered to its periphery sufficiently high to the periphery of the other stone, or rubber, to leave a narrow space a channel around and wide enough to allow the rice or grain projected by the Convex surface from between the two planes of the rubber to undergo a little further projection from the convex surface of the said rubber.

any part of the rubber and the porphyry of the other rice. But the same
disqualification may thereby be made accessory or auxiliary to one of the
usual purpose as the rest of the hulling, nutting or the grinders in flour or other
mills. But I will be very manifest that there must be a prepared or vacant
place left in the circumference of the said roller, in order to admit the escape of the
grains of rice, into a hopper leading to one or both of present to you
a degree of prepared or completed, in between the said rice and the porphyry of
the same. With the hulled rice there is to undergo the operation just desig-
nated must be carefully admitted as the same is placed in the hopper
(perhaps one ton of Staff to four bushels of rice, but experience must determine
the appropriate quantity according to the condition and quality of the rice.)
a considerable proportion of the clearest and heaviest of the rice Staff taken
in the operation will after the original roughup is worse down on the
rice be ground up itself. Similarly to the short or bran in wheat or rice.

If the rice in the first operation should not
as it comes out from between the rubber prove to be satisfactorily bright
or cleaned it must after it has been further well cleaned be returned
to the same rollers with a fresh supply of Staff to undergo again the same
operation but when expectation is desperate, it being understood that after
any operation of the kind, forming and removing may be considered as
next to essential, it would be better to have one or more additional sets of
rollers and the more the surfaces of the rollers can be increased by variation
from a horizontal place of course the same ought to accelerate the op-
eration by the prolongation or greater duration of the friction which is to
consummate it. After the rice is deemed sufficiently cleaned from the in-
impellentes it will then have to undergo the same process as in other mills, by
utilization, screening, to separate the flour, small rice and whole rice as it
is eliminated, by forming or the rice in rice, nutting, or nutting, & about
the rice of the fine flour, a silicing and thereby polishing and polishing, & it
will then again form itself and finally packing it into the barrels.

The rollers above alluded to have been con-
sidered as placed horizontally but for the rubber so used in the hulling
process, the bearing of barley being referred to as non an equally proper

United States Patent

Patent No.: X8768

What I Claim as my ^{own} invention and not previously known in the Cleaning
and preparing of rough rice or Paddy by the above described process is the
application of Stone by itself, or with wood or any other material, with which
is the Stone, can act in combination together with the air and proper ad-
mixture of the Chaff to aid and promote the friction necessary and desira-
ble for the proposed object Washington City 6th April 1835
